UNITED STATES PATENT OFFICE.

HEINRICH TSCHUDY, OF ENNENDA, SWITZERLAND.

DRAWING FRAME FOR SPINNING MACHINERY.

Application filed November 3, 1921. Serial No. 512,589.

To all whom it may concern:

Be it known that I, HEINRICH TSCHUDY, a citizen of the Republic of Switzerland, and residing at Ennenda, in the Canton of Glarus, Republic of Switzerland, have invented certain new and useful Improvements in Drawing Frames for Spinning Machinery, of which the following is a specification.

This invention has for its object to provide an improved roller weighting mechanism, more particularly for weighting the leather-covered pressure rollers of flyer frames and spinning frames.

The method usually adopted for weighting such pressure rollers consists in supporting weights directly, by means of hooks or the like from the rollers, or in connecting weighted pivoted levers to the rollers by means of links or the like. The weights or levers may be connected respectively to each roller or may be supported from a saddle which in turn is supported on two rollers.

For cleaning the rollers of the "fly" which tends to accumulate upon them, light wooden cloth covered cleaning rollers, resting upon the pressure rollers, are usually provided.

Such wooden cleaning rollers serve only for the purpose of cleaning the rollers, but it has been proposed to use a wooden cleaner roller for the two front pressure rollers only, which rollers are weighted in the usual manner, and to support a cloth covered metal roller on the third of the pressure rollers, such metal roller serving the double purpose of cleaning the said third roller and of weighting it.

According to the present invention the only weighting of the pressure rollers is effected by means of a single heavy cloth covered cleaning roller, such roller resting upon the front or the two front pressure rollers.

This invention is illustrated in a constructional example in the accompanying drawing in which the improved roller-weighting mechanism of this invention is illustrated as applied to a ring frame.

In the improved roller weighting mechanism illustrated, the light cleaning roller or shaft, is dispensed with and is replaced by a weighting roller B' which has likewise a cloth covering E but is considerably heavier, being made, for instance, of iron or other metal whose weight and dimensions

are such that in spinning the requisite pressure is exerted upon each single stretch of yarn F. This heavy weighting roller B', used in substitution for the light wooden cleaning roller, effects, in addition to this section as 60 a weighting means, the cleaning of the pressure roller A by means of the covering E in a still more certain manner than does the light wooden roller.

Owing to the cloth covering E, the improved roller weighting mechanism has a very elastic effect, and owing to the rolling friction, it causes only the very slightest wear and tear of the preferably leather-covered pressure roller A, which is very 70 advantageous. Each axle journal of the heavy weighting roller B' bears against a strong guide C' which is fixed adjustably on the side plate h of the hind roller. This guide C' has a forked support KK for receiving the weighting roller B' when the pressure roller A is relieved of weight.

At its front end the guide C' has an adjustable supporting screw C'.

From the above description it will be perceived that the improved mounting of the rollers considerably simplifies the construction of the spinning frame owing to the elimination of many parts and that the pressure roller, instead of being under sliding friction as before, is now under rolling friction with consequent economy of power, and that it receives the weighting pressure in an elastic manner, so that, owing to the considerably diminished wear and tear, it 90 has a much longer life.

A further advantage is that the weighting roller can be removed without having to detach any parts. With this improved roller weighting mechanism there are less 95 breakages of the yarn than before and consequently a better thread or yarn is obtained than has hitherto been possible.

In spinning machines with horizontal drawing frames the U-shaped metal guides are eliminated and the roller may be guided in the vertical guide and held on two rollers in which case a friction of pivots is relieved.

What I claim is:

1. In a drawing frame, the combination 105 with a front pressure roller, of a top-clearer-roller resting upon the said roller and of sufficient weight to supersede the usual weights and appertaining devices.
2. In a drawing frame, the combination 110

with a front pressure roller and the framing of said drawing frame, of a top-clearer of sufficient weight to supersede the usual weights and appertaining devices, a metal guide member of U-shape whereof one side-limb serves as a guide for said top-clearer and weighting-roller, and its other side-limb is formed at its free end as a bearing adapted to receive and support said

clearer and weighting-roller in the inoperative position of the latter. 10

In testimony whereof I have affixed my signature in the presence of two witnesses.

HEINRICH TSCHUDY.

Witnesses:

CHR. MILLIEN,

HERMANN TEUBOR.
